SILVER RECOVERY UNIT FOR THE RETRIEVAL OF SILVER FROM HYPO SOLUTIONS

Leonard W. Gacki, 25 Wellington Terrace,
White Plains, N.Y.

Filed Mar. 1, 1962, Ser. No. 69,099

Term of patent 14 years

(Cl. D16—2)

FIG. 1 is a perspective view of the silver recover unit for the retrieval of silver from hypo solutions embodying my new design.

FIG. 2 is a side elevational view thereof.

FIG. 3 is a front elevational view thereof.

FIG. 4 is a perspective view from the left and above thereof with the cover removed.

FIG. 5 is a side elevational view of the unit thereof with the collection discs in raised position.

The rear, not shown, is substantially plain and unornamented.

I claim:

The ornamental design for a silver recovery unit for the retrieval of silver from hypo solutions, as shown and described.
